UNITED STATES PATENT OFFICE.

FRANK JONES, OF SALT LAKE CITY, UTAH.

DIGGING MACHINE.

Application filed January 26, 1925. Serial No. 4,781.

The present invention relates to a digging and conveying apparatus of the type known as a mechanical mucker, used in mining operations and the like, where material is to be removed from a point and loaded into suitable cars or other means of transportation.

A leading object of the present invention is the provision of a machine of this character, so constructed that it will pick up the material in a suitable shoveling device, transport the material to an opposite side of the machine, and discharge the said material at said latter point into a mine car or other receptacle which is to remove the material from the scene of operations.

A further object of the invention is the provision of a digging and conveying means, the range of movement of which lies in a single vertical plane, thereby requiring a relatively small, or narrow space within which to operate.

A still further object of the invention is the provision of improved mechanism for causing the operation of the machine quickly and efficiently, the said mechanism being compactly arranged upon the machine so that it will not require extensive space within which to operate.

With the above and other objects in view, the invention consists of the parts and combinations of parts as set forth in the appended specification and claims.

Referring to the drawings forming a part of this application, in which like reference characters indicate like parts in the several views:

Fig. 1 is a side elevation of my improved digging machine,

Fig. 2 is a plan view of the same,

Fig. 3 is a rear elevation of the same,

Fig. 4 is an end elevation of the shovel, showing the position of parts when the shovel is at the lower end of the tracks in digging position,

Fig. 5 is an end elevation of the shovel, showing the position of the parts when the track section is raised and the bail disengaged from the end gate of the shovel,

Fig. 6 is a vertical sectional view on the line 6—6 of Fig. 4,

Fig. 7 is a fragmental side elevation of the upper end of the track, showing the shovel just about to discharge its contents,

Fig. 8 is a vertical sectional view of a detail of construction, and

Fig. 9 is a vertical sectional view of the ends of the movable track sections, showing the rubber bumpers positioned therein.

Referring to the drawings, the numeral 1 indicates the main body or truck of the present machine. This truck is mounted upon suitable wheels 2, running upon tracks 3, the said tracks being of the usual character employed in mining or digging operations. Two wheels are provided at each side of the machine in the manner shown. Carried by the frame 1, are air cylinders 4, one of said cylinders being placed at each side of the machine. Suitable pistons, not shown, are mounted within said cylinders, and attached to each of said pistons is a piston rod 5 which projects through the rear of the cylinder, and passes through an elongated slot or opening formed in the upper end of the clamp 6, suitable bolting means 5^a holding said piston rod firmly in position within said slot and permitting the automatic adjustment or movement of the machine to accommodate for curves or variations in the gauge of the mine tracks 3. At its lower end, each clamp is curved as at 6^a to form one section of a clamping body, the other section being provided by a separate plate 7 having a like curved end 7^a. Bolting means 7^b are used to connect the clamps 6 and 7, and, as will be seen from Fig. 3, the clamping sections of each of said clamps are positioned surrounding and grasping the adjacent rail 3. The inner surfaces of the clamping members 6^a and 7^a may be serrated or roughened to increase the gripping action on the rails 3. By this means, the clamping members, and in turn the piston rods are fixed, and the wheels of the machine are movable to and fro upon the tracks 3, upon the introduction and discharge of fluid pressure within the cylinders 4, as will be hereinafter more fully described.

Mounted upon the body or truck 1 is a bed plate 8, said bed plate being connected to said body near its rearward end through a king bolt 9. At its forward end the said bed plate rests upon an arcuately curved channel bar 10 which extends across and is attached to the forward end of the truck 1. As best shown in Fig. 8, a band 11 is bolted to the front of the said bar 10, this

band being engaged by two hook bolts 12 and 12, attached to each side of the bed plate 8, the said hook bolts being thus provided to hold the said bed plate down upon the truck and prevent any upward movement of the plate during the digging operations.

Attached to the bed plate 8 of the machine are two forward structural supports 13 and 13 and two rear structural supports 14 and 14, one of said front and rear supports being disposed on each side of the machine. The rear supports 14 and 14 have their upper ends bent toward the rear, and near the upper end of each of the same are mounted bearings 15 and 15, which receive bearing pins 16 and 16 carried by tracks 17 and 17, one section of track being thus pivotally mounted upon each of said structural members 14. The tracks 17 are formed of channeled members in substantially the form and shape shown in the drawings, the channeled faces of the same being adapted to receive wheels or rollers 18 carried on opposite sides of a shovel 19, which latter is thus adapted to move back and forth along and between the said channeled tracks 17 and 17. Carried by each of the said track members 17 is a suitable roller 20 which bears against the forward surface of the adjacent structural support 13 for the purpose of giving support to the shoveling means during the digging operation, and taking the strain off the pivot pins 16. Near the lower end of the said channeled tracks 17 and 17 are two lugs 21 and 21 connected by a cross-piece 22, as shown, for the purpose of keeping the two channeled tracks properly spaced and to thus keep the gage of the tracks true. Attached to the exterior of each track is a pivoted bail 23 which is connected by means of a rope or cable 24 with a spring 25, which latter is connected by a second rope or cable 26 to a lug 27 on one of the supports 13. The bail 23 passes around the rear of the shovel 19 and bears against the end gate 19^a during the digging operation, the said bail thus serving as a means for holding the said end gate closed during the digging operation. Attached to the upper end of each of the forward supports 13 is a curved segment 28 which acts to engage said bail 23 upon the lifting of the tracks and shovel, and to move the bail from its position against the end gate 19^a, thereby permitting opening of the said gate when the shovel is to be dumped, as will be hereinafter described.

A latching means is provided to retain the end gate 19^a of the shovel in closed position until the latter is to be dumped. Referring to Figs. 4 to 7 inclusive, which show in detail the latching means, the numeral 29 designates a latching bar, pivotally mounted at 30 to the right of the center of the bar, to

a lug 31 attached to the end gate 19^a, the upper end of said lug 31 being offset to receive the said bar 29. Riveted to the sides of the shovel at the back edge thereof are lugs 32 and 33. The lug 32 opens upwardly, 70 and the lug 33 opens downwardly, each lug being adapted to receive an end of the bar 29. When the bar 29 is positioned, as shown in Figs. 4 and 5, with its opposite ends engaging the lugs 32 and 33 respectively, the 75 end gate 19^a is locked in closed position. At the top of one of the tracks 17 is provided a cam plate 34, against which the outwardly extending, upwardly movable end of the bar 29 is adapted to ride when the shovel reaches 80 a position at the rear of the tracks, the said bar projecting to the side of the shovel a sufficient distance to be thus engaged by the cam. The riding of the bar 29 over the cam 34 will cause movement of said bar about 85 the pivot 30 from engagement with the lugs 32 and 33, thus in turn releasing the end gate 19^a and allowing the said gate to swing open and discharge the contents of the shovel, as the shovel reaches the end of its 90 backward travel.

For the purpose of moving the track and shovel from side to side, an air cylinder 35 is secured to the truck frame 1, just back of and between the upright supports 13-13. 95 A piston (not shown) is mounted within the said air cylinder, the said piston having piston rods 36 and 37 which project from opposite ends of the cylinder 35, and carry at their ends rollers 38 and 39, respectively. A 100 chain 40 fastened at one end to the rear side of cylinder 35, passes around the roller 38 on the end of piston rod 36, and then forward to a lug 41, which is rigidly secured to the bed plate 8. A similar chain 40^a passes 105 around the roller 39, on the piston rod 37 and is likewise connected to the lug 41. Air is admitted to each end of the cylinder 35 through pipe connections 42 leading from a four-way valve 43. As air is admitted to either end of the cylinder 35, the piston will be forced toward the opposite end, causing the piston rod and roller thereon to be thrust outwardly, in turn drawing the opposite rod and roller inwardly. One end of the chains 110 40 and 40^a being attached to the stationary cylinder 35 which is mounted upon the truck 1 of the machine, and the opposite ends being attached to the lug 41 on the movable bed plate 8, movement of the piston rods 115 120 will, through the said chains, act upon the lug 41 to move the bed plate 8 and all structure mounted thereon from side to side about the king bolt 9, the said bed plate having slots 44, 45 and 46 therein to provide for 125 the cylinder 35 and other parts attached to the fixed body or truck 1.

The tracks 17, upon which the shovel runs, are raised and lowered by means of wire ropes 47, attached to lugs 48 near the lower 130

end of each of the tracks. Each rope passes up around a hoisting sheave 49 at the top of adjacent main standards 18, then down and around sheaves 50 carried by the piston rods 51 projecting from the air cylinders 52 mounted upon the machine at opposite sides thereof, and from said sheaves up to the top of the main frame to which it is fastened at 53. A piston of the usual type is mounted within each air cylinder 52 to be acted upon by the air admitted to the cylinder on opposite sides of the said piston, the air being admitted at opposite ends of the said cylinder. When the shovel and tracks are to be raised, air is admitted to the top of each cylinder 52 thereby forcing the pistons therein downwardly. The piston rods 51 and the sheaves 50 carried thereby are drawn downwardly, and due to the attachment of the ends of the wire ropes 47 to the main frame and to the tracks, such downwardly movement of the pistons and sheaves will cause an upward movement of the tracks and the shovel carried thereby. While the weight of the tracks and shovel should be sufficient to lower them, such lowering may be facilitated by admitting air to the lower end of the cylinders 52 and raising the pistons therein. Air is admitted to each end of said cylinders through pipe connections 53 and 54, leading from a four-way valve 55.

Each of the main cylinders 4, 35 and 52 are connected by suitable pipes with separate four-way valves 56, 43 and 55 respectively, the said valves being under the control of the operator of the machine for accomplishing the various operations of digging and loading. Each of the said valves is connected through suitable branch supply pipes to the main air line of the mine. While I have referred to the use of air as the operating fluid, it is to be understood that steam or other fluid pressure could likewise be used.

For the purpose of preventing the dirt from falling and lodging between the sides of the shovel and the tracks during the digging operation, I have provided a curved piece of iron 57 riveted to the top of each track near the lower end thereof. Rubber bumpers 58 are mounted at both ends of each track, serving as abutments against which the wheels of the shovel will strike when the shovel reaches the limit of its movement in either direction.

In the operation of the present machine, the latter is moved upon the mine tracks to a position near the muck pile or other location of the material to be removed, the clamps 6 are attached to the rails 3 of the track, the shovel is in the lowered position, and the machine is ready to operate. Air is admitted through the valve 56 to the cylinders 4, thus forcing the machine and

the shovel ahead and into the pile of material. Air is now admitted through the valve 55 to the tops of the cylinders 52, and through the ropes 47 the tracks 17 and shovel 19 are raised to the elevated position shown in dotted lines in Fig. 1. Upon the raising of the tracks the segment 28 engages the bail 23 and disengages the latter from its latching position against the end gate 19a of the shovel. Upon the tracks 70 reaching their upward limit of movement, the shovel will run by gravity toward the rear of the machine, the latching bar 29 will be released by the cam 34 and the end gate will be free to swing open and dump 80 the material within the shovel, the dumping being facilitated by the sudden abutment of the shovel rollers against the rubber bumpers 58 at the rear of the tracks 17. The tracks are now lowered and the shovel 85 will run by gravity to the forward end of the same, it being also understood that air has been admitted to the rear ends of the cylinders 4 through the valve 56 and the machine thereby drawn to the rear. The 90 latching bar 29 will drop into latched position upon the closing of the end gate, since one end of said latching bar is heavier than the other end because of the pivot point of said bar being off center, and as the shovel 95 reaches the forward ends of the tracks, the bail 23 will latch in place, and the shovel is again ready to be forced into the pile of material. If it is necessary to swing the shovel from side to side, such movement is 100 controlled by the admission of air through the valve 43 to either end of the cylinder 35, and thereafter the tracks and shovel are raised, and the shovel dumped as hereinbefore described.

In the machine thus described, it will be noted that the movement of the shoveling means takes place within substantially a single vertical plane, that is, the shovel digs, and is raised, and carried rearwardly without any side movement of the same. The action is very similar to the action of a man in throwing dirt over his shoulder, the advantage of this movement being that it permits operation of the machine within a limited space, this being particularly advantageous in mining operations. The operation of the machine is easily under the control of a single operator, the movement of the digging and conveying means is efficient and rapid, and the machine will handle the material in a much quicker and more efficient manner than other machines of this character now in use. The parts are strongly constructed, and the machine is not likely to 115 become disabled through dealing with heavy, or rocky material.

It will be noted, also, that although the shoveling and lifting actions are independent of each other, yet, when necessary, as 120

in the case of encountering a large rock, the shovel can be gradually lifted any distance desired while being forced ahead at the same time; in other words, the two actions can be combined when necessary, giving a sort of scooping action.

It is to be understood that the form of my invention herein shown and described is to be taken as a preferred example of the same, 10 and that various changes may be made in the shape, size, and arrangement of parts without departing from the spirit of my invention or the scope of the subjoined claims.

Having thus described my invention, I 15 claim:—

1. A machine of the character described, comprising a base, a track pivotally mounted thereon, a shovel carried by the free end of the track, an anchor, extensible means 20 connecting the base and anchor, means to expand and contract said extensible means for the purpose of crowding the shovel, and means carried by the track in engagement with the base for relieving strain on the 25 track pivot during crowding of the shovel.

2. A machine of the character described, comprising a base, an inclined track movably mounted thereon, a shovel mounted on the track, an anchor, extensible means connecting the base and anchor, means for expanding and contracting the extensible means for the purpose of crowding the shovel, means to elevate the track to discharge the shovel, and buffers carried by 30 the track and designed to engage the base whereby to relieve the track pivot of strain 35 during crowding.

3. The combination with a track, of a 40 wheeled base movable thereon, a power cylinder carried by the base, a piston movable therein and a piston rod carried by the piston, a clamp secured to the track and connected to the piston rod, and fluid pressure means to energize the power cylinder to 45 move the base upon the track, said clamp being provided with a transverse slot within which the piston rod is free to move lateral-

ly, whereby to compensate for lateral irregularities of the track.

4. A machine of the character described, 50 comprising a base, an inclined track pivotally mounted thereon, a shovel mounted on the track, a pivoted bail for retaining the shovel in loaded position at the lower end of the track, means for retaining the bail in 55 position, and means for reversing the inclination of the track, said reversal of the track serving to automatically release the bail to discharge the shovel.

5. In a machine of the character described, the combination of a wheeled base; means for moving said base to and fro; a platform pivoted to said base, said platform being movable in a horizontal plane; means carried by said base for moving said platform; a plurality of structural uprights mounted upon said platform, two of said uprights being at the rear thereof; a trackway extending from front to rear of the machine, said trackway comprising two spaced 70 channeled tracks, each of said tracks being horizontally pivoted upon one of said rear structural uprights; means connecting and spacing said tracks; a shovel carried by said trackway and operable thereupon, upon 75 movement of said trackway in a vertical plane; rollers upon opposite sides of said shovel, said rollers being mounted within the channeled face of said tracks; a cam surface at the rear of one of said tracks; an end 80 gate at the rear of said shovel; latching means for said end gate, said latching means being released by said cam surface; a pivoted bail at the forward end of said trackway, 85 said bail engaging and supporting the shovel when the latter is at said forward end; means for releasing said bail upon raising of the shovel; and means for moving said trackway in a vertical plane to cause movement of the shovel thereupon. 90

In testimony whereof he hereunto affixes his signature.

FRANK JONES.
